CHARLES M. DAY AND JOHN ANDERSON, OF HOPEDALE, MASSACHUSETTS,
ASSIGNORS TO DRAPER COMPANY, OF PORTLAND, MAINE, AND HOPE-
DALE, MASSACHUSETTS.

MOLDING-MACHINE.

SPECIFICATION forming part of Letters Patent No. 714,285, dated November 25, 1902.

Application filed October 21, 1901. Serial No. 79,327. (No model.)

To all whom it may concern:

Be it known that we, CHARLES M. DAY and JOHN ANDERSON, citizens of the United States, and residents of Hopedale, in the county of 5 Worcester and State of Massachusetts, have invented an Improvement in Molding-Machines, of which the following description, in connection with the accompanying drawings, is a specification, like characters on the drawings representing like parts.

In a certain type of apparatus for facilitating the construction of molds for metal-foundering the drag is made by placing the flask on a stripper-plate firmly supported on a suitable frame, said plate having apertures therein for the different parts of the pattern to extend through and project above the face of the stripper-plate, the latter providing for the parting face of the mold. The pattern is 15 mounted on a carrier or support which is movable toward and away from the stripper-plate, and when the pattern is in operative position relative to the stripper-plate the molder fills the flask thereon with sand and 20 rams it in usual manner. When the drag is 25 finished, the carrier is moved away from the stripper-plate to thereby "draw" the pattern from the drag, as it is technically termed, and the latter is lifted off and turned over in readiness to receive the cope, which may be 30 constructed on a similar machine or on what is technically termed a "flat-back." A flat-back is a flat plate with such portions of a 35 pattern rigidly secured thereto as can be readily drawn from the mold.

In order to produce accurate work with such molding-machines, it is absolutely necessary that the pattern coact precisely with the apertured stripper-plate during the formation 40 of the mold, and when the pattern is drawn from the mold its movement away from the stripper-plate must be smooth and even and at right angles thereto or the fine outlines of the mold will be damaged.

Again, a molding-machine of the type referred to is commonly used in connection with a large number of patterns and their corresponding stripper-plates, and as the latter are preferably made of a standard thickness 45 the pattern-plate must be moved into a fixed

position every time a mold is made on the machine, and means must be provided to compensate for wear of the moving parts of the machine in order that this definite and fixed operative position of the pattern may always 55 be secured.

Our present invention relates to molding-machines of the type hereinbefore referred to; and it has for one of its objects the production of means for effecting a smooth and 60 steady movement of the pattern absolutely at right angles to the face of the stripper-plate when the pattern is drawn.

Another object of our invention is the provision of means for attaining the exact and 65 definite positioning of the pattern relative to the stripper-plate when the mold is being constructed, compensating for wear of the moving parts of the machine or for any slight variation in the thickness of the stripper-plate. 70

Other objects of our invention relate to the enlargement of the character of work which may be performed by a given machine, the improvement and simplification of the mechanical structure thereof, and increased efficiency and facility of operation. 75

The various novel features of our invention will be fully described in the following specification and particularly pointed out in the subjoined claims.

Figure 1 is a front elevation, partly broken out, of a molding-machine comprehending one embodiment of our invention, the stripper and pattern plates being omitted. Fig. 2 is a right-hand end elevation thereof partly 80 broken out and in section. Fig. 3 is a detail, partly in section, on the line 3 3, Fig. 2, looking toward the right and showing a portion of the mechanism for operating the pattern-plate carrier. Fig. 4 is a horizontal section 85 through the base of the carrier and the adjustable connection between it and the operating means, taken on the line 4 4, Fig. 2. Fig. 5 is a top or plan view of the frame of the molding-machine shown in Figs. 1 and 2, 90 omitting the pattern-plate carrier, the stripper and pattern plates and stool-plate also being omitted; and Fig. 6 is a perspective view of the pattern-plate carrier detached. 95

In the drawings the stripper and pattern 100

plates are omitted, though their position is indicated in dotted lines, Fig. 2, and the pattern-plate carrier is shown in its operative position. We have herein shown the frame supported upon and rigidly secured to two like ends A A of suitable size and shape to properly and firmly support the superstructure and the operating parts of the machine, the superstructure or upper part of the frame consisting of $\square$ -shaped front and back portions, Figs. 1 and 2, connected by a grid-like base. The front and back pieces comprise horizontal and parallel heads A² and depending legs A³, the heads forming a support for the stripper-plate, (partly indicated by dotted lines at S, Fig. 2,) the lower ends of the legs being cast integral with the base, which comprises transverse end bars A', intermediate a', and longitudinal webs a², the longitudinal tops a³ of which project above the end and intermediate bars A' and a', as clearly shown in Fig. 2, for a purpose to be described. The heads A² are each provided with a centrally-located and external boss A³, each of which has rigidly secured to it a depending guideway, (shown as a large and preferably cylindrical bar A⁴,) which extends downward nearly to the bottom of the frame taken as a whole, and heavy brackets A⁵, bolted to the grid-like base of the superstructure, have large hubs A⁶ to embrace the guideways and support them at their lower portions. These oppositely-located and parallel guideways outside the front and back pieces of the frame constitute rigid bearings for the pattern-plate carrier, to be described, and guide it in its movement up and down in the operation of the machine.

Referring to Fig. 2, it will be seen that the upper portion of the frame is open at its ends, so that a stripper-plate much longer than the heads or supports A² may be used with a corresponding pattern-plate, the open ends of the frame permitting the use of a pattern-plate of any length within reasonable limits. This is a very important and valuable feature of our invention, as the scope of the work of a given machine is thereby greatly extended, it being manifest that the length of the pattern to be used is only limited by the inherent strength and rigidity of the stripper and pattern plates necessary therefor.

The "pattern-plate," by which term we mean a suitable metallic plate to which is secured the pattern or parts thereof which project through openings in the stripper-plate during the formation of the mold, is mounted upon a vertically-movable carrier, and herein the carrier is shown as substantially U-shaped (see particularly Fig. 6) and comprising upright arms C, connected at their lower ends by a transverse base portion C¹, the tops of the arms being laterally extended or made T-shaped, as at C', to constitute parallel supports, on which the pattern-plate P (partly shown in dotted lines, Fig. 2) will be supported and secured, the carrier being movable

vertically within the frame of the machine, as clearly shown in Fig. 2, and the carrier is slidably connected with the guideways by heavy hubs c c' at the lower and upper ends of the arms, respectively, and projecting outwardly therefrom, the said hubs having a sliding fit on the guideways A⁴.

The width of the pattern-plate is of course limited by the space between the stripper-plate supports A², as will be manifest from Fig. 2; but, as has been stated, the length of the pattern-plate is not restricted to the length of the machine-frame from end to end, as the extended ends of the pattern-plate may project as far as is necessary or desirable beyond the open ends of the frame.

The guideways support the carrier at its upper and lower portions and on opposite sides thereof, and the actuating means for the carrier is connected with the latter between its points of support—viz., the guideways—and at the lower portion of the carrier, thus greatly economizing space and also permitting a stool-plate to be employed when molds are being made requiring the use of stools.

The stool-plate, if one be used, and which may be of usual construction, is not herein shown, is supported on the upper faces a³ of the webs a², and by making the stool-support as a plurality of narrow longitudinal surfaces we are enabled to reduce the machining or planing of these surfaces to a very material extent.

It will be manifest that the stool-plate may extend as far beyond the ends of the frame as necessary to correspond to any given pattern and stripper-plates, although for such extended stool-plate a slightly-different form of actuating-handle will have to be used, to be referred to hereinafter.

The grid-like base of the superstructure is provided with depending lugs a⁵, (see Fig. 1,) which form bearings for an operating rock-shaft D, extended in the direction of the length of the machine and projecting beyond one of the end frames, as shown in Figs. 1 and 2, said shaft being shown in Fig. 3 as provided with a pair of crank-arms d, rigidly secured thereto and connected by a crank-pin d¹, which is extended through the upper end of a bent link D¹, the lower end thereof being pivotally connected with the pattern-plate carrier at or near the base thereof and symmetrically between its supporting-guideways, the link moving in a vertical plane intersecting the base and the upright arms to prevent any twisting of the carrier when it is moved.

Referring to Figs. 4 and 6, the central portion of the carrier-base C¹ is enlarged, as at c², and provided with an elongated aperture c³, a pivot-pin c⁴, Fig. 4, being passed transversely through the sides of the enlargement c² and held from rotation by a set-screw 10, Fig. 3. Within the opening c² an eccentric c⁴ is loosely mounted on the pivot-pin c³, the periphery of the eccentric being embraced by

the split end d^4 of the link, and said split end is adapted to be clamped tightly upon the eccentric by means of a suitable clamping-bolt d^8 , engaging the threaded ears d^2 of the 5 split portion. One end of the eccentric is herein shown as made polygonal, as at c^5 , outside of the end of the link and between the latter and one of the sides of the extension c^x of the carrier-base.

10 From the foregoing description and from the drawings it will be manifest that by rotating the actuating-shaft D in the direction of the arrow 6, Fig. 2, the link D^x will be swung to the left and downward, effecting 15 the downstroke of the carrier from the position shown in the drawings and when the machine is in use operating to draw the pattern from the mold.

10 The extreme upward position of the carrier—that is to say, when the pattern-plate is in precisely the proper position to coöperate accurately with the stripper-plate—is at a definite and fixed distance below the upper surface of the stripper-plate support, and it will 25 be manifest that wear of the parts of the machine—as, for instance, wear of the pivot d^x for the upper end of the link or slight wear of the actuating-shaft bearings a^5 —will prevent the exact positioning of the pattern-plate 30 unless some means be provided to compensate for such wear. This compensation in our present invention is provided for by the adjustable connection between the link and the carrier, as by loosening the split end d^4 35 of the link the eccentric c^4 can be turned in one direction or the other to accurately position the top of the carrier, the rotative movement of the eccentric being readily effected by a wrench or spanner applied to the polygonal portion c^5 thereof, and after the adjustment has been effected the clamp-bolt d^8 will 40 be set up to tightly clamp the eccentric and link immovably together.

When the carrier is elevated, as shown in 45 the drawings, the upper pivot d^x will be off center relative to the actuating-shaft, and a stop 15 (see dotted lines, Fig. 2, and full lines, Fig. 5) is preferably provided to limit further throw of the crank-arms d to the right.

50 The carrier is herein shown as provided with a stiffening-web c^6 , (see dotted lines, Fig. 2, and full lines, Fig. 6,) and a short depending connection c^7 extends from the stiffening-web to the base C^x adjacent the enlargement c^x 55 of the latter.

The downward stroke or draw of the carrier is determined by means now to be described, and such means is made readily and accurately adjustable, so that the draw may 60 be varied according to the character of the pattern, some patterns requiring a greater downward movement of the carrier than others in order to properly separate them from the stripper-plate after they have been drawn 65 from the mold. A hub d^{10} , having a radial socket d^{12} for the operating handle or bar d^{13} , is rigidly secured to the projecting end of the

actuating-shaft D, and said hub has an annular enlargement d^{14} , which is surrounded by a split collar d^{15} , adapted to be clamped upon the hub enlargement by a suitable clamp-bolt d^{16} , extended through threaded holes in the adjacent ends of the collar. One of these ends, as d^{17} , is shouldered at its end and is adapted to engage a fixed lug or 70 stop 30 on one of the base-bars A' of the frame superstructure. Now when the mold has been completed and the molder is ready to draw the pattern he grasps the handle or bar d^{13} and pulls it toward the front of the 80 frame, thereby rotating the actuating-shaft D in the direction of the arrow 6, Fig. 2, to lower the carrier, as has been described, and after the pivotal connection d^x between the link and the crank-arms d has passed dead- 85 center the weight of the carrier and the pattern-plate attached thereto will tend to complete the downward movement of the carrier, and such movement will continue until the part d^{17} of the clamp-collar d^{15} brings up 90 against the stop 30.

To vary the draw or downward movement of the carrier just described, it is only necessary to slacken up the clamp-screw d^{16} and turn the collar d^{15} in one direction or the other and then tighten the collar when the shoulder d^{17} is in the desired position, and it will be noted that this adjustment can be made with the greatest nicety necessary or desirable. So, too, the means provided for 100 adjusting the connection between the link and the carrier can be varied to a hair's breadth, if desired, this perfection of adjustment in the latter case being of great importance. 105

We have herein shown sheet-metal guards G secured to the bosses A^3 and hubs A^6 and extending well around the vertical guideways A^4 to protect the same from sand during the construction of the mold, these guards 110 by keeping the sand away from the guideway and from the coöperating hubs on the carrier reducing very greatly the wear of such parts.

Sometimes sand will drop down from the 115 top into the machine, and to direct the same away from the guideway we have herein shown the upright arms C of the carriage as provided with inclined openings c^{10} , the upper ends of which are between the T-shaped 120 portions C' and the adjacent hubs c', any sand dropping down on this part of the machine falling into the chutes or openings c^{10} and being directed by the inclined bottoms thereof toward the interior of the machine and 125 away from the guideways. We also prefer to bevel the tops of the guide-hubs c' to aid in shedding sand should any accidentally fall thereupon.

Referring to Fig. 2, it will be noticed that at 130 all times the operating mechanism is located below the horizontal plane of the stool-plate supports a^3 , so that no matter what the shape of the stool-plate or its length the carrier-ac-

tuating mechanism will be below the same and will never interfere with it, and consequently the length of the stool-plate is not restricted in any manner by the structure of the machine.

If a long stool-plate and corresponding stripper and pattern plates be used, the actuating handle or bar d^{13} will be removed and a bent bar used instead to clear the projecting ends of the plates.

It will be noticed that the point of application of the actuating means on the carriage is so located that the movement of the latter either toward or away from the stripper-plate will be even and uniform, the draft being equally distributed throughout the carrier, and this, in connection with the guideways, provides for an absolutely steady and smooth movement of the carrier and insures the maintenance of the pattern-plate in a true horizontal position absolutely parallel with the face of the stripper-plate.

In Figs. 1 and 2 we have shown strong spiral springs S^{60} attached at their ends to the upper part of the main supporting-frame and secured at their lower ends to hooks 90 on the central portion of the carrier-base C^x , such springs compensating in a measure for the weight of the carrier and the parts movable therewith and rendering the manual operation of the apparatus easier for the molder.

Referring to Fig. 2, it will be seen that the actuating force is transmitted from the operating-shaft D to the pattern-carrier through the link D^x , the lower end of the latter being connected with the carrier midway between its sides and similarly relatively to the ends thereof in order that the draft of the carrier shall be central and the power applied uniformly to the different portions of the carrier.

In order to secure as direct transmission as possible from the shaft D to the carrier and as nearly as may be in a vertical direction, the shaft is located above the pivot-pin c^3 and as nearly vertical over it as convenient, and the curvature of the upper end of the link permits this positioning of the operating-shaft D .

Our invention is not restricted to the precise construction and arrangement of one practical embodiment thereof herein shown and described, as the same may be modified or rearranged without departing from the spirit and scope of our invention.

Having described our invention, what we claim as new, and desire to secure by Letters Patent, is—

1. In a molding-machine, an open-ended frame having parallel portions at its top to support a stripper-plate, vertical, oppositely-located guideways on and wholly exterior to the frame, at its front and back and substantially midway between its ends, a carrier for the pattern-plate, hub-like extensions on the carrier at its top and bottom and projecting

outward beyond the front and back of the frame, to embrace and move vertically on the guideways, and means to actuate the carrier, the open ends of the frame permitting the use of stripper and pattern plates longer than the frame.

2. In a molding-machine, an open-ended frame having parallel portions to support a stripper-plate, vertical and oppositely-located guideways on the exterior of the frame at its front and back substantially midway between its ends, a U-shaped carrier for the pattern-plate, outwardly-extended hubs on the upright portions of the carrier, to embrace and slide vertically upon the guideways, and actuating means for the carrier.

3. In apparatus of the class described, a carrier comprising a transverse, centrally-apertured base having upturned arms laterally extended in parallelism at their upper ends, to support a pattern-plate, actuating means for the carrier, including a link, a pivot-pin on the carrier-base midway between its arms and extended across the aperture in the base, and an adjustable connection between the link and pivot-pin, said connection being located in the aperture of the base equidistant from its sides.

4. In apparatus of the class described, a vertically-movable pattern-plate carrier, actuating means therefor including an operating-shaft, an adjustable friction-clamp thereon having a stop-shoulder, and a fixed stop to coöperate therewith and regulate the drawing stroke of the carrier.

5. In apparatus of the class described, a vertically-movable pattern-plate carrier, actuating means therefor including an operating-shaft, a split collar thereon having a stop-shoulder, a fixed stop to coöperate therewith and regulate the drawing stroke of the carrier, and means to clamp the collar in adjusted position on the shaft.

6. In a molding-machine, an open-ended frame having oppositely-located, external guideways mounted on the parallel front and back portions thereof, a U-shaped carrier for the pattern-plate, said carrier comprising a base and upright portions, hubs on its upright portions to embrace and slide vertically upon the guideways, and actuating means for the carrier connected with the base thereof midway between the upright portions, the latter rising from and being connected with the base at their lower ends only.

7. In a molding-machine, a frame having upright front and back portions connected by a base and adapted to support a stripper-plate at the top, stool-plate supports on the base, an open-ended pattern-plate carrier vertically movable within the frame, and actuating means for the carrier, supported by the frame and located wholly below the stool-plate supports.

8. In a molding-machine, a frame, vertical, oppositely-located guideways thereon, and a

U-shaped carrier for the pattern-plate, the upright portions of said carrier having T-shaped extensions to sustain the pattern-plate, and sand ducts or passages in the said upright portions, to deflect sand inward away from the guideways.

5 In testimony whereof we have signed our

names to this specification in the presence of two subscribing witnesses.
